COMBINATION WALKING AID AND INVALID SUPPORTER

Charlie R. Williams, P.O. Box 415,
Kosciusko, Miss. 39090

Filed Feb. 11, 1966, Ser. No. 1,012

Term of patent 14 years

(Cl. D83—1)

Fig. 1

Fig. 2

FIG. 1 is a perspective view of a combination walking aid and invalid supporter, embodying my new design; and FIG. 2 is a side elevation thereof.

I claim:

The ornamental design for a combination walking aid and invalid supporter, as shown.
